MUTE FOR WIND INSTRUMENTS

Walter C. Martin, Niles, Ohio

Continuation of application No. 14,831 (now abandoned), filed March 15, 1948. This application May 24, 1950, Serial No. 163,820.

2 Claims. (Cl. 84—400)

This invention comprises novel and useful improvements in a mute for wind instruments, more particularly to an attachment for modifying the sound characteristics of musical instruments of the horn family, and the principal object of this invention is to provide new and improved mutes of this character.

A further object of this invention is to provide a mute which may be quickly and accurately, but detachably applied to the flared end of a horn, trumpet or the like for modifying the sounds emitted by said instruments; which shall be very flexible in its adjustment and variation of the instrumental tones; and which is compact and inexpensive.

This application is a continuation in part of an application filed by me on September 4, 1946, Serial Number 694,717, for Mute, and a continuation of an application filed by me on March 15, 1948, Serial Number 14,831, for Mute For Wind Instruments, the aforesaid application having been abandoned.

In the drawings accompanying this specification and forming a part of this application, there is shown, for purposes of illustration, several embodiments which my invention may assume, and in these drawings:

Figure 1 is a side elevational view of an embodiment of the invention:

Figure 2 is a vertical longitudinal sectional view, showing the construction of Figure 1 applied to the horn of an instrument, the mute being shown locked in its closed position.

Figure 3 is a transverse horizontal sectional view taken substantially from the plane of the section line 3-3 of Figure 2;

Figure 4 is a horizontal sectional view taken substantially from the plane of the section line 4-4 of Figure 1;

Figure 5 is a top plan view of another embodiment of the invention. 40

Figure 6 is an elevational view, parts being broken away to show the interior.

broken away to show the interior construction thereof, and showing the invention applied to the horn of an instrument, the mute being in its wide open position; 45

Figure 7 is a horizontal sectional view taken in plan from the bottom of the mute; and Figure 8 is an elevational view similar to

Figure 5 is an elevational view, similar to Figure 6, but showing the parts in the closed position of the mute.

Referring particularly to Figures 1 through 4 of the drawings, the embodiment therein shown to disclose the invention comprises a mute 10 which is adapted for mounting in the flared

2

opened end 12 of a musical instrument such as a horn, as shown in Figure 2. The mute consists of a hollow conical body 14 which is closed by a detachable base 16 and has an open end 18.

5 Secured in any suitable manner, as by an adhesive or the like, upon the smaller or lower end of the conical body 14, are a plurality of strips 20 of cork or the like which are preferably longitudinally disposed upon the body and provide a cushioning and securing means by which the mute is removably attached within the throat of the horn 12. Obviously, any suitable number of these securing strips may be provided, and while cork has been given as a satisfactory material, it is evident that various other substances could be employed. Further, although the strips are shown as disposed longitudinally of the body, it is evident that they may be positioned in various manners thereon and 10 in various arrangements as is found to be most expedient for the use intended.

As shown in Figure 2, the strips 20 are disposed longitudinally of the body 14, and are secured to the body by adhesive 22.

15

As shown best in Figure 2, the base 16 is provided with an axial boss having inner and outer extensions 22 and 24, respectively, through which 25 extends a bore 26 constituting an oilless guide for slidably receiving a rod 28 having a headed lower end 30 to prevent withdrawal of the rod upwardly through the guide. The outer extremity of the rod 28 is threaded as at 32 and is provided with a finger-grip ring 34 by which the 30 rod may be manipulated as set forth hereinbelow.

A hemispherical cap 36, of any suitable material, is provided with an annular beaded rim 38 of a diameter sufficient to seat upon and engage the extremity of the horn 12 for which the mute is adapted.

Rigidly secured to the interior surface of the member 36 in any suitable manner, as by spot welding or the like, is a concavo-convex member 40 which serves the dual function of assisting in securing the member 36 to the screw-threaded end 32 of the rod 28, an also providing means for locking the member 36 to the end of the horn 12 in the position shown in Figure 2. For this purpose the member 40 is provided

For this purpose, the members 36 and 40 are provided with aligned, axial apertures through which the screw-threaded portion 32 extends, the finger-grip ring 34 comprising one abutment for retaining these members upon the rod, while an adjusting nut 42 serves to detachably lock the parts in assembled position. A coiled spring 44 surrounds the rod 28 between the abutment 24 and the nut 42, and serves to yieldingly bias the parts into their extended position as shown in Figure 1.

In order to clamp and lock the parts into their closed position as shown in Figure 2, the base 16 has detachably secured thereto, as by screws 46, a pair of vertically disposed standards 48 whose upper ends terminate in laterally but oppositely disposed flanges 50. Depending from the lower surface of the member 40, are a pair of downwardly struck portions 52 which provide straps for receiving the flanges 50 when the mute cover 36 is rotated relative to the base 14, as indicated by the arrows 54 in Figure 3.

From the foregoing, the operation of the device will be readily understood. The mute is inserted in the mouth of the horn 12, and is retained therein by the frictional engagement of the strips 20 upon the inner surface of the horn. The spring 44 normally urges the member 36 to its open or outer position as shown in Figure 1. In order to vary the tonal characteristics of the horn it is merely necessary to grip the finger-grip portion 34 and press thereon to urge the mute cover 36 inwardly, to thereby vary the effective opening or clearance between the end of the horn 12 and the cover 36, thus modifying and muffling the tonal qualities of the horn. When it is desired to close the mute, either when mounted upon the horn or when removed therefrom, it is merely necessary to rotate the cover 36 relative to the base 14 in the direction of the arrows indicated in Figure 3 at 54, while depressing the cover 36 upon the base against the opposition of the spring 44, whereupon the flanges 50 will engage in the straps 52 for locking the parts in their closed position as shown in Figure 2.

Attention is next directed to the embodiment of the invention shown in Figures 5 through 8. In this form of the invention the numeral 110 designates generally the entire mute assembly which is shown attached to the flared open end 112 of a musical instrument. The mute consists of a body 114 which is a hollow cone having a detachable base 116 and a truncated open end 118.

Upon the outer surface of the body 114 are disposed one or more rows of suction cups 120, in any suitable position, for firmly anchoring the body 114 in the horn 12, while a plurality of cork or strips of other material 122, extending longitudinally upon the body 114, provide a further cushioning and frictional securing means for maintaining the mute in the horn.

Obviously, any desired number of suction cups and strips may be provided, and the spacing of the same may be varied to suit the individual use for which mute is intended.

The base 116 is axially and inwardly extended as at 124 to provide an oilless guide bearing bore 126 terminating in an enlarged recess 128. A rod 130, with threaded extremities 132 and 134, is freely slidable in the bore 126 and is biased inwardly of the body 114 by a spring 136 surrounding the rod and having one end seated in the recess 128 and its other end bearing against a retainer head 138 secured upon the threads 134. A hemispherical cap 140 of any suitable material is reinforced by the convex member 142 which is threaded upon the end 132, and a knob 144 serves as a control means for the bell 140. The circumference of the bell 140 is rolled over as at 146 to form a bead to which is attached a gasket 148 of any desired material.

As will be readily apparent from Figure 7, the gasket 148 is preferably made up of a number of arcuate, resilient members such as felt or rubber, the terminal ends of which are spaced

5 to provide slots 150 between the ends of the gasket sections. The slots 150 define radial openings for the escape of musical tones from the horn when the device is in fully muted position as shown in Figure 8. The gasket sections may be suitably attached as by adhesive or the like to either the bead 146 of the cover 140, or to the adjacent rim of the horn 112.

10 The operation and functioning of the device will be readily understood from the foregoing description. In the employment of the implement, the body 114 is engaged with the open end 112 of a horn, leaving a restricted passage between the coaxial adjacent conoidal surfaces of these elements, which passage muffles and modifies the sound of the instrument. By means of the action of the spring 136, the bell 140 normally seats upon the rim of the horn as shown in Figure 8, further muffling and altering the characteristics of the instrumental note. By retracting the bell 140 against the action of spring 136 through manipulation of the knob 144, the muffling and modifying effects of the bell can be varied at will. A rapid reciprocation of the bell produces a wah-wah sound of variable frequency.

25 In view of the foregoing, it will be apparent to those skilled in the art that I have accomplished at least the principal object of my invention, and it will also be apparent to those skilled in the art that the embodiments herein described may be variously changed and modified, without departing from the spirit of the invention, and that the invention is capable of uses and has advantages not herein specifically described; hence it will be appreciated that the herein disclosed embodiments are illustrative only, and that my invention is not limited thereto.

CLAIM:

1. A mute for musical instruments comprising a body having a portion adapted to fit within the bell of a musical instrument, a mute carried by said body and having a peripheral portion positioned adjacent and generally corresponding to the terminal periphery of said bell and being movable toward and away from said terminal periphery, connection means connecting said mute and said body and normally holding them against disassembly regardless of the position of said mute, said connection means providing for free sliding movement of said mute relative to said body so that said mute may be freely moved to cause said peripheral portion to approach or recede from said terminal periphery and thus provide for change of the tonal characteristics of said musical instrument, resilient means urging said mute toward one extreme position relative to said body, and means for locking said mute in the opposite extreme position.

2. A muting device for musical instruments comprising a body member having a portion adapted to fit within the bell of a musical instrument, a hollow cap member movably carried by said body member and having a peripheral portion corresponding in configuration to the terminal periphery of said bell, means connecting said cap and body members for holding them against disassembly regardless of the relative position of said members, said connecting means providing free sliding movement of said cap member relative to and on said body member to provide for free movement of said cap member from an inner position wherein the said peripheral portion of said cap member is in engagement with the said terminal periphery of said bell to an outermost position wherein said per-

2,690,092

5

eral cap member portion is spaced axially from said bell terminal periphery to a maximum extent, and spring means for urging said cap member to its outermost position.
